UNITED STATES PATENT OFFICE.

HERBERT H. STEELE, OF MARCELLUS, NEW YORK, ASSIGNOR TO THE MONARCH TYPEWRITER COMPANY, OF SYRACUSE, NEW YORK, A CORPORATION OF NEW YORK.

TYPE-WRITING MACHINE.

1,110,082.

Specification of Letters Patent. Patented Sept. 8, 1914.

Application filed January 2, 1912. Serial No. 668,869.

To all whom it may concern:

Be it known that I, HERBERT H. STEELE, citizen of the United States, and resident of Marcellus, in the county of Onondaga and 5 State of New York, have invented certain new and useful Improvements in Type-Writing Machines, of which the following is a specification.

My present invention relates generally to 10 platens and to paper feeding and controlling mechanism for typewriting machines and its general object is to provide improved devices of the character referred to.

More specifically one object of the invention is to provide a divided or sectional platen of improved construction which has no exterior, central support but which nevertheless minimizes the sagging tendency at the point of junction of the two sections 20 which has heretofore been a defect except in those constructions wherein an intermediate platen support is provided. With this latter construction, however, it is impossible to employ overlapping work sheets; for which, 25 however, my present invention is particularly adapted.

Another object of the invention is to provide improved means for feeding and controlling separate work sheets arranged side 30 by side and overlapping.

Another object is to provide for the differential feeding or advancement of such sheets.

Another object is to provide means for 35 connecting and disconnecting automatically the parts of a divided platen and for concurrently throwing into and out of operative position paper feeding devices adapted to certain of the work sheets.

40 Other objects will subsequently appear.

To the above and other ends my invention consists in the features of construction, combinations of devices and arrangements of parts hereinafter described and particularly 45 pointed out in the claims.

One form of my invention applied to a Monarch typewriting machine of the wide platen style is illustrated in the accompanying drawings, wherein—

50 Figure 1 is an end elevation of the upper part of a Monarch typewriting machine embodying my invention, parts being omitted and parts broken away. Fig. 2 is a frag-

mentary detail front elevation of a feed roller for a transfer medium or carbon strip. 55 Fig. 3 is a diagram illustrating the overlapping arrangement of the work sheets. Fig. 4 is a fragmentary front elevation of the rear support of a device hereinafter termed a roll carrying frame. Fig. 5 is a 60 fragmentary front elevation of the carriage of the machine with my invention applied thereto. Fig. 6 is a fragmentary central longitudinal sectional view of the platen. Fig. 65 7 is a transverse view taken on planes represented by the broken dotted line $x-x$ in Fig. 5 and looking in the direction of the arrows at said line. Fig. 8 is a plan view of a guide for the transfer medium or carbon paper. Fig. 9 is an end view of the carbon 70 or transfer roll and its support. Fig. 10 is a sectional view taken on planes represented by the broken dotted line $y-y$ in Fig. 9 and looking in the direction of the arrows at said line. Fig. 11 is a fragmentary vertical section 75 view showing the mounting at one end of a work sheet roll holder.

As best appears from Figs. 1 and 5 the main frame of the typewriting machine comprises posts 1 supporting a top plate 2 from which rise curved standards 3 to which are secured grooved track-ways 4 connected through anti-friction balls 5 with a slide bar 6 comprised in a platen frame, carrier or carriage which further includes end bars 7 85 and 8. The end bars provide bearings for a platen axle 9 on which are mounted end to end the two sections or parts of a divided or sectional platen as most clearly appears in Fig. 6. The left-hand platen section comprises a core 10 and a sheath 11 and has operatively connected to its left-hand end a line spacing ratchet wheel 12 with which suitable line spacing mechanism, such as the ordinary devices comprising a pawl 13 operated by a handle 13^a, are adapted to operate. A platen head 14 provided with an elongated, rightwardly extending hub 15 is secured by wood screws 16 to the right-hand end of the core 10. The elongated hub 15 100 surrounds the axle 9 and is secured in fixed relationship therewith by a pin 17, said pin also securing together the axle 9 and the left-hand platen section. The right-hand platen section comprises a core 18 and a 105 sheath 19, the sheath 19 closely abutting the

sheath 11 so that the two platen sections form a substantially continuous surface which is free and unobstructed throughout the combined lengths of the platen sections. Secured by wood screws 20 to the left-hand end of the right-hand platen section is a platen head 21 which comprises an inwardly extending sleeve 22, said sleeve surrounding and bearing on the hub 15. As hereinafter explained the left-hand platen section is adapted to turn independently of the right-hand section. During this turning movement the hub 15 will rotate while the sleeve 22 is stationary.

The construction provides two comparatively long inter-related bearing surfaces for the platen sections and it is found in practice that sufficient rigidity of bearing is thus attained to enable the stationary intermediate platen support of prior constructions to be dispensed with. The long and comparatively extensive bearing minimizes yielding or spring at the point of junction arising from the action and re-action of the force of gravity and of the spring pressed feed rollers, this yield or spring having heretofore resulted eventually in the disarrangement or throwing out of alignment of the platen sections which, of course, in order to obtain the best results, should always be maintained in substantially co-axial alignment. Abutting against the right-hand end of the hub 15 is a long sleeve or collar 23 which surrounds the axle 9 and extends rightward through the right-hand platen section and through the end bar 8, being secured to said end bar by a screw 24 which, however, does not engage with the axle 9, said axle being free to turn in the sleeve 23, said sleeve being adapted to take up end thrust. Wood screws 25 secure a platen head 26 to the outer end of the right-hand platen section, said platen head having a hub 27 and bearing on a hub 28 of a toothed or gear wheel 29 which wheel, in turn, bears on the sleeve 23. The gear wheel 29 is rigidly secured to the right-hand platen section by a screw 30 which passes through the hub 27 and engages in a tapped opening in the hub 28. The gear wheel 29 is at the left of the end bar 8 and outside said end bar is a second toothed gear wheel 31 provided with a hub 32 which receives a cross pin 33 by which the wheel 31 is secured to the platen axle 9. Secured to the outer right-hand end of the axle 9 by a set screw 34 is a finger wheel 35 of ordinary construction by which the left-hand platen section and at times both the platen sections together may be turned for line spacing or other purposes. However, additional devices are provided which expedite the turning of one or both platen sections through considerable distances to give a continuous feed to the work sheets. Said devices comprise a crank arm 36 which is suitably

secured to a sleeve or hub portion 37, said hub portion loosely surrounding and bearing on the hub 32 and being confined between a boss 38 projecting leftward from the wheel 31 and a collar 39 secured by a screw 40 to the right-hand end of the hub 32 (Fig. 6). A spring 41 is coiled around the hub 37 and is connected at its ends respectively to the collar 39 and the crank arm 36. The spring tends constantly to urge the crank arm in a forward direction and normally maintains it in engagement with a stop pin 42 projecting laterally from the end bar 8.

In normal position the crank arm 36 inclines forward and upward as shown in Fig. 1. The upper end of the crank arm is provided with a handle or finger piece 43 by which it may be manipulated and swung rearward about the axis of the spindle or axle 9 as a center. Near its axis the crank arm has fulcrumed to it at 44 a depending pawl arm 45 provided at its upper end with a forwardly extending tail 46 which normally contacts with the stop pin 42, the lower end of said pawl arm terminating in a tooth 47 which is adapted to engage with teeth of the wheel 31, the pawl being in the same fore and aft plane as the wheel as is shown in Fig. 5. The construction is such that normally the pawl tooth is maintained separated from the wheel 31 by reason of the engagement of the tail 46 with the stop pin 42. When, however, the crank arm 36 is turned rearward the tail separates from the stop pin and permits the pawl tooth to drop into engagement with one of the teeth of the wheel 31, thereby connecting the wheel with the crank arm 36 and transmitting motion of said crank arm to said wheel and from it to the left-hand platen section and at times also to the right-hand platen section. During return movements of the crank arm under the action of its restoring spring the back of the tooth 47 which is preferably rounded as shown will slide inoperatively over the teeth of the wheel 31 and will separate from said teeth when the tail 46 is brought into contactive engagement with the stop pin 42 as shown in Fig. 1. The two platen sections are normally disconnected from each other but means are provided for automatically connecting them so that they will turn together, said means comprising an elongated pinion 48 arranged at the lower rear side of the toothed wheels 29 and 31 and of sufficient length to engage with both wheels but normally out of mesh therewith. The pinion 48 is mounted to rotate on the lower end of a spring-pressed swinging lever member 49 which is pivotally supported on a rod or shaft 50, this shaft preferably being the feed roller releasing rock shaft. The member 49 terminates at its lower end in a downward extension 51 and at its upper end in a pawl

or locking tooth 52 which normally is maintained in engagement with the teeth of the wheel 29 by reason of the forward pressure exerted constantly against the upper arm 5 of the lever 49 by a coiled spring 53. The rear edge of the extension 51 is adapted to coöperate with a cam bar 54 arranged on the top plate and suitably secured thereto and extending rightward beyond the top 10 plate, its overhanging portion being screwed to a supporting arm 55 fast to the lower track-way 4. The right-hand end of the bar 54 inclines rearward, providing a cam edge 56 which intersects the path of the extension 51 and is so located that as the right-hand platen section approaches the point at which the types will strike it, the extension will engage with the cam edge 56, the result being that as leftward movement of the 15 platen is continued thereafter the extension will be forced forward, swinging the member 49 on its pivot. By this swinging movement the locking tooth 52 is disengaged from the wheel 29, unlocking the right-hand 20 platen section, and the pinion 48 is brought into mesh with the toothed wheels 29 and 31, thereby connecting the two platen sections. The pinion partially engages before the locking tooth entirely disengages, thus 25 preventing accidental relative displacement of the platen sections. During further leftward movement of the platen the extension 51 will ride along the cam bar 54 and the pinion 48 will thus be maintained in operative 30 position so that a turning or line spacing movement communicated to the left-hand platen section either by the usual line spacing devices or by the handle 43, will be transmitted to the right-hand platen section; the two sections turning as a single 35 unitary platen. The platens will remain thus connected as long as the right-hand platen section is in position to coöperate with the types. When the platens are 40 stored toward the right and the right-hand platen section passes out of the type-printing field, the lever 49 will be swung by the spring 53 back to the position shown in Fig. 1, thereby uncoupling the two platen sections and locking the right-hand platen section against turning movement.

To coöperate with the two platen sections, paper feeding or controlling devices are provided, the devices that coöperate with one 45 platen section being distinct from and operative independently of the paper feeding and controlling devices of the other platen section. The paper feeding means preferably comprise two sets of the usual feed or 50 pressure rollers, the support for each set comprising a pair of the usual lugs 57 projecting forward from the slide bar 6. Pivoted at 58 to each lug is an arm 59 (Figs. 5 and 7), the arms forming two pairs, each 55 pair supporting a shaft 60 carrying the sec-

tions of a main feed roller 61 which is spring-pressed toward the platen. The lugs 57 also pivotally support at 62 arms 63, each pair of arms 63 carrying a shaft 64 whereon are mounted the sections of a secondary feed roller 65 which is also spring-pressed toward the platen. Each platen section may further be provided with a spring-pressed paper apron or deflector 66 provided with openings through which the 70 feed rollers may coöperate with the platen. Of course, single feed rollers may be employed one for each platen section but preferably there are sets as described, each set comprising a main feed roller and a secondary feed roller, each set being arranged to coöperate with one end portion or section of the platen so that a sheet may be fed around each end of the platen from the introductory side toward the printing point. 75 It will further be understood that from some aspects the end portions or sections of the platen may be considered as each constituting in itself a platen element or platen. Each set of paper feeding devices is provided with its own releasing means, the means for the left-hand set being controlled by devices mounted outside the left-hand end bar 7 while the corresponding devices for the right-hand set are mounted outside the 80 end bar 8. Comprised in the releasing means for the left-hand platen section is a rock shaft 67 corresponding with the rock shaft 50, the two rock shafts 50 and 67 taking bearings in lugs 67² projecting forward 85 from the slide bar 6. Each rock shaft has projections or lugs 68 which when the rock shaft is turned coöperate with lugs 69 on the arms 59 to throw off or release the associate main feed roller and through said arm 90 to release the secondary feed roller.

The means for turning each rock shaft are preferably of the usual construction and comprise a crank arm 70 secured to the rock shaft and operative by an arm 71 pivotally 95 connected to the crank arm 70 and provided with a finger piece or actuator 72. The arm 71 is pivotally connected to a crank arm 73 pivoted at 74 to the adjacent end bar of the platen carrier. The pairs of arms 73 and 71 100 each compose a toggle which is normally broken but when the associate finger piece 72 is pulled forward, the toggle is straightened, locking the parts. During the movements of their actuators 72 from normal to 105 abnormal position the rock shafts 67 and 50 are rocked, causing the lugs 68 to act on the lugs 69, swinging down the arms 59 and 63 and releasing the main and secondary feed 110 rollers carried thereby. When the feed rollers are released the associate deflectors 66 will be released and their forward edges will drop against the bottom of a cutout 115 formed lengthwise at the top of the usual platen scale plate 76 (Figs. 5 and 7). The 120

125

130

keys or actuators 72 may be separately actuated and thus will independently control the sets of feed rollers.

My present invention is particularly adapted for use with a plurality of work sheets having an overlapping arrangement, and these work sheets, together with an interposed transfer medium or carbon sheet, are preferably in roll form and supported 10 on a frame which is mounted on the platen carrier.

More specifically the present invention is especially adapted for commercial billing of the sort in which a record sheet is fed 15 around the right-hand platen section and receives totals and other data from bills or invoice sheets which are introduced over and fed around the left-hand platen section. In the system for which the present form of the 20 invention was especially designed the blanks of the bills or invoices are printed at regular intervals on a continuous sheet or strip as are the blanks on the record or total sheet; and these two sheets slightly overlap at their 25 inner edges so that by means of a reproducing medium introduced between them, preferably a strip of carbon paper also in roll form, certain items may be written simultaneously in duplicate on the two work sheets. There will be, then, three roll 30 holders on the supporting frame before mentioned. Said frame comprises two parallel vertically disposed end plates 77 (Figs. 1, 5 and 7) which are connected at their forward lower sides by a tie rod 78, and about 35 their middle upper portions by a tie rod 79 the ends of which are threaded and adjustably secured to the end plates by pairs of clamping nuts 80 at opposite sides of the end 40 plates, the construction affording an adjustable connection. At their rear lower sides the plates 77 are adjustably connected by a vertically disposed cross bar 81 which receives near each end a screw 82 passing 45 through a vertical slot 83 in an inturned ear 77^a on the associate end plate 77, the construction being such as to afford a vertical adjustment of the bar 81 (Fig. 4). About 50 its middle this bar 81 carries a flanged roller 84 which bears on a bar or track-way 85 formed with vertical slots 86 which receive 55 screws 87, said screws entering the rear faces of the standards 3 and adjustably securing the track-way 85 thereto, thus providing for supporting the frame comprising the plates 77 at its rear side. The front side 60 of said frame is partly supported on a rod or bar 88 which is preferably the usual paper finger rod of the machine, said rod 65 extending longitudinally of the platen above the same and being secured at its ends to the end bars of the carriage. The plates 77 are provided with hub portions 89 which fit over the bar 88 and are detachably pinned 75 thereto by removable pins 90. The end

plates 77 curve down behind the platen and forward of the slide bar 6, being provided with inwardly off-set extensions 77^b (Fig. 1) which are formed with vertical slots 91 that fit down over the shanks of headed 70 screws 92 supported in the two outermost lugs 67^a. The detachable frame, as will be seen from Fig. 5, extends substantially throughout the length of the combined platen sections and while it is supported on 75 the carriage and moves therewith, its weight, together with the weight of the roll holders and rolls which it carries, is to a considerable extent taken off the ball bearings 5 by the supplementary roller bearing 84 and 86 the stationary track bar 85 on which said roller runs during back and forth traveling movements of the carriage. The relative adjustability of the roller 84 and its track bar provides for suitably regulating the co-active 85 engagement between the two parts.

The frame comprising the plates 77 provides a support for a bill sheet 93 and a record or summary sheet 94, these sheets being in roll form as shown in the drawings 90 and supported at opposite end portions of the frame so that their inner end portions overlap somewhat as will be understood best from the diagrammatic view shown in Fig. 3. The bill sheet roll 93 is arranged 95 at the rear of the frame and the record sheet forward thereof on the frame but to the right of the other, these rolls being on roll holders which are of similar construction and mounting although oppositely arranged 100 so that a description of one will be understood as applying equally well to both.

Referring to Figs. 1, 5, 7 and 11, each roll holder comprises a tubular core 95 and flanges 96 and 97, the inner flange or 105 head 96 having a hub 98 and the core 95 being fast to said flange which in turn is secured to a tubular bearing shaft 99 by a pin 100 passing through the hub 98. The shaft 99 receives at its ends plugs or bearing 110 pins 101, one bearing pin engaging in a bearing opening in the adjacent plate 77 and the opposite bearing pin being seated in an open mouthed slot 102 in the other plate 77. This affords ready removal of the 115 shaft 99 and the roll holder supported thereon. In order to retain the shaft in place the pin 101 which is seated in the open slot 102 preferably extends some distance outside said slot and is engaged by a spring 120 mounted latch or hook 103 pivoted at its lower end at 104 to the end plate and terminating in a hook 103^a which latches over the pin 101 and is maintained in operative position by a spring 105. Stops 106 limit the 125 swinging movements of the latch 103. A lateral finger piece 107 provides for swinging and unlatching the hook so that the pin 101 may be lifted out of the bearing slot. With the pin removed, one of the stops 106 130

will prevent undue movement of the latch 103 due to the spring 105. The outer flange 97 of each roll holder is separate from the core 95 and is provided with take-up devices which permit of adjustment of the flange lengthwise of the core and also act as a brake for the associate roll holder to prevent too free unwinding of the rolled work sheet. As shown in Fig. 11 the end 10 of the core 95 which is adjacent the flange 97 is provided with a plug 108 which bears on the shaft 99. The flange 97 has fixed to it an outwardly extending hub 109 which bears on the pin 101, said hub being cupped 15 as indicated at 110 and receiving an expansion spring 111. Surrounding the hub 109 is a cap 112 which is forced outward by the spring 111 against the inner face of the adjacent plate 77. The cap 112 has a slot 113 20 which receives a pin 114 on the hub 109, the pin and slot connection preventing relative rotary movement between the hub and cap but permitting endwise movements between them. It will be understood that by reason 25 of this construction the flange 97 is adjustable relatively to the flange 96 of the roll holder so that they can accommodate between them rolled work sheets varying somewhat in width, these work sheets being 30 rolled on paste-board cores 115 which are slipped over the tubular core 95 and frictionally engage therewith, while the end of the roll of paper is engaged by the flanges 96 and 97. Further it will be apparent that 35 the pressure of the spring 111 causes the cap 112 to frictionally engage the plate 77 so that it will act as a drag or brake during turning movements of the roll. As will be observed from Fig. 5 the roll holders occupy 40 a little more than half of the length of their respective shafts. If found desirable these shafts may be supported outside the roll holders and suitable intermediate supports are illustrated in Figs. 5 and 7, the support 45 for the rear shaft 99 being an upright arm 116 having a bearing seat at the top and being secured at its lower end by a screw 117 to the bar 81. The support for the forward shaft is an upright arm 118 which in 50 turn is supported at its lower end on the frame rod 88.

The loose end of the roll 94 is led down from the rear of the roll as shown in Fig. 7, passing forward over the rod 78 and 55 down behind the platen and between the same and the right-hand deflector 66 and thence upward at the front side of the platen. The paper from the roll 93 is guided downward from the front side of 60 the roll passing over the usual paper table 119 and between it and the rod 78, thence over the left-hand deflector 66 and upward at the front side of the platen, the portion 65 of the bill sheet which overlaps the record sheet being between said record sheet and

the platen as will be understood from Fig. 3, which is a diagram, viewed from the front, of the arrangement of the sheets at the back of the platen.

The overlapped sheets 93 and 94 pass upward at the front of the platen and then through a slot-way 120 formed by a vertically disposed guide plate 121 and a parallel cutter bar or blade 122 which is arranged forward of the guide plate and has 75 a flaring lower end and a beveled upper or cutting edge as indicated at 123. The ends of the guide plate and the cutter bar are turned rearward, providing ears 124 which are secured by screws 125 to the inner 80 faces of the forward portions of the plates 77. Near each end the cutter bar has secured to it a depending guide finger 126 which overlaps the scale plate 76 and guides the outer end of the associate work sheet 85 upward into the slot-way 120. One or more supporting arms 127 (Fig. 7) may be secured to the back of the guide plate 121, said arms extending horizontally rearward and being provided with hook-like ends 90 which engage the rod 88.

In addition to the paper feeding mechanism heretofore described, additional paper controlling devices are provided for cooperation with the work sheet 93, said devices 95 comprising two clamping fingers which are adapted to cooperate with the guide plate 121 through slots 128 in the cutter bar 122. Each clamping finger comprises a tongue 129 secured to a rock shaft 130 and bent as 100 shown in Fig. 7, the lower end portion of each finger being provided with a flexible sheath 131 of rubber or the like. The rock shaft 130 bears at its left-hand end in a lug 77 on the left-hand plate 77, and at its 105 right-hand end in a bracket 132 riveted to the blade 122. The clamping fingers when inoperative are separated from the plate 121, as in Fig. 7, but may be swung down to clamping position by devices which 110 comprise a crank arm 133 secured to the left-hand end of the rock shaft 130 outside the plate 77 and connected by a link 134 with a crank arm 135 secured to the rock shaft 115 67. When the feed rollers that cooperate with the left-hand platen section are released the clamping devices will be concurrently rendered operative and will be locked in clamping relationship with the plate 121 through the straightening of the toggle that 120 72. is controlled by the left-hand actuator 72.

The transfer or carbon strip that is introduced between the overlapping portions of the bill sheets is indicated in the drawings by the reference number 136, said carbon strip being wound in a roll which is carried by a roll holder supported on upwardly extending arms 137 provided with hubs 138 pinned to the tie rod 79. As illustrated in Figs. 9 and 10, said roll holder 130

comprises a tubular core 139 detachably secured to the ends wherof are heads or flanges 140, each flange having fixed to it a plug 141 which is beveled to facilitate its entrance into the tube 139, the plugs frictionally engaging with the tube. The plugs bear on a shaft 142, one end of which has secured to it the hub 143 of a crank arm 144 provided with a handle 145, the shaft 142 being provided with a radial pin 146 which engages a slot 147 in the right-hand plug or core piece 141, the construction being such that motion of the shaft is transmitted to the core piece and roll holder. The hub 143 bears in the right-hand arm 137 while the opposite end of the shaft bears in the left-hand arm 137 and outside said arm is provided with a groove 148 which is engaged by a key hole slot 149 formed in a slideable latch 150, said latch being provided with another slot 151, the slots coöperating with headed pins 152 which maintain the latch slidably connected with the outer face of the left-hand arm 137. The upper end of the latch is turned outward to provide a finger piece 153 by which the latch may be slid up and down. When the latch is in the position of Figs. 9 and 10, it locks the shaft 142 and prevents its withdrawal from its supports. By pushing up the finger piece 153 the enlarged part of the slot 149 is brought in alinement with the shaft which may then be withdrawn to permit of the removal of the roll holder.

35 The carbon paper 136 is wound on the core 139 and its free end is drawn down from the back of the roll, passing between the overlapped portions of the sheets 93 and 94, since the supports 137 and the roll holder 139, 140 are arranged about centrally and so that they will be in the plane of the overlapped portions of the hill sheets and just to the right of the division between the two platen sections, the overlapped portion of the sheets 93 and 94 and the interleaved carbon sheet coöperating with the left-hand end portion of the right-hand platen section. The carbon sheet or strip 136 is guided downward and through a slot-way 154 (Fig. 5) formed in the rearwardly inclined upper end 155 of a deflector or curved plate 156 which is riveted or otherwise secured to the cross rod 78 and extends downward behind the platen, curving forward under the same 55 and terminating at the front side of the platen below the printing point (Fig. 5). It will be observed that the deflector 156 is arranged in the space between the inner ends of the deflectors 66.

60 The carbon paper passes down and around the platen outside the deflector 156. As will be observed from Fig. 5 there is a space between the inner ends of the two sets of paper feeding and controlling devices for the 65 sheets 93 and 94, and the carbon strip oc-

copies this space so that it is outside of the control of said sets of devices and may be controlled by special devices comprising a short feed roll 157 which, as shown in Fig. 2, is supported on parallel arms 158 and 159 which bear loosely on the rock shaft 50 and are held from endwise movement thereon by a collar 160 interposed between the arms 158 and 159 and secured to the rock shaft by a screw 161. The arm 159 is provided with a downward and forward extension 159^a which is adapted to coöperate with a projection or step 54^a on the cam bar 54, said projection having beveled ends or cams 54^b and being located so as to coöperate with the extension 159^a when the carbon paper is brought within the field of the printing types. Normally the feed roll 157 hangs down in inoperative position, as shown in Fig. 1; but when the endwise travel of the carriage brings the extension 159^a into engagement with the step 54^a, the frame 158, 159 is swung forward, bringing the roller 157 into coöperative engagement with the back of the deflector 156. This causes the feed roll to engage operatively with the overlapped portion of the left-hand one of the work sheets and the interleaved carbon strip, and should the sheets be advanced at this time the motion will be transmitted to the interleaved carbon strip 136 which will also be advanced. At other times when the sheet 93 to the left of the carbon strip is opposite the printing point, the line spacing operation will advance only the sheet 93; 100 while at times when the portion of the work sheet 94 to the right of the carbon strip is opposite the printing point, a line spacing operation may advance the sheet 94 and the sheet 93 together without affecting the carbon strip, which will remain quiescent.

In adjusting the work sheets, the record or summary sheet 94 being next to the platen surface is first passed around the right-hand platen section after the carriage has first 110 been shifted to the left so that the two platen sections are connected. The carriage is then shifted to the right and the sheet 93 is passed around the platen and adjusted. The interleaved carbon sheet 136 is adjusted 115 last while the carriage is positioned as in Fig. 5 so that the feed roll 157 is operative. All three sheets having been adjusted to extend above the cutter bar 122, each sheet may then be manipulated separately to bring it to the proper position and the projecting end portions severed. The sheets 93 and 94 in the commercial billing system, for which the present form of my invention was especially devised, are continuous strips of 120 printed blanks, a plurality of the blanks of the sheet 93 being used in connection with one blank of the sheet 94. A shipping label or tag may be printed simultaneously with the heading of the blank on the sheet 94 130

by means of a transfer slip or carbon backing, this printing, of course, being at the right of the overlap so as to not interfere with the sheet 93. Prior to the simultaneous printing of the shipping tag and the heading the carriage is shifted to the left to connect the two platen sections and the left-hand feed rollers are thrown off while the clamp is on, so that when the platen sections are turned for spacing between the lines of the tag and heading only the tag and the sheet 94 will be advanced, the sheet 93 remaining quiescent. The tag and the heading of the sheet 94 having been finished, said sheet is line spaced to the first blank line below the heading, the tag is removed, the carriage shifted to the right and the left-hand release lever restored; after which the first entry on the bill sheet 93 is printed, this entry being the order number. The carriage is then shifted to the left in position to print on the overlapping portion of the two sheets which simultaneously receive the department number. A similar line spacing operation following this printing operation will advance all three of the sheets. The carriage is then restored to the right and the platen is given a continuous turning movement by means of a rearward pressure on the handle 43 until the first order line of the bill sheet is brought opposite the printing point. It will be understood that during this continuous advance movement of the bill sheet, the sheet 94 and carbon sheet 136 will remain quiescent.

When all the entries on the bill sheet blank have been printed it is line spaced or advanced to bring the bottom or "total" line of the blank opposite the printing point; and the carriage is then moved leftward so that the printing operation will take place on the overlapping portions of the two sheets after which a single line spacing operation follows, advancing each of the three sheets a unit distance. The carriage is next shifted to the right and the handle 43 is operated to advance the sheet 93 continuously until the printed blank is at the severing position whereupon it may be torn off. The next and subsequent invoice blanks, one for each department on the particular order in hand are filled in and entries made on the overlapping portions of the sheets in the way described. When the order is completed if any additional memoranda be desired, they are entered on the summary blank 94 to the right of the overlapping portions of the sheets. Thereupon, while the carriage is at the left-hand side so that the overlapping portions of the sheets are to the left of the printing point, the handle 43 may be operated to continuously advance the sheet 94 until the blank for the first order has passed upward beyond the cutting edge 123, whereupon the

first or printed blank on sheet 94 may be severed. During this advance movement the sheet 93 and carbon strip remain quiescent. When in the course of the feeding operations the end of the carbon strip or ribbon has been brought above the cutting edge 123 the crank handle 145 may be turned backward by hand to rewind the carbon strip until its end is only a short distance above the printing point. This rewinding operation does not affect either work sheet. It may be repeated at intervals until the carboned surface has been exhausted after which the exhausted portion may be torn off against the cutting edge 123. Thus means are provided for differentially advancing a plurality of continuous rolled work sheets, two of said sheets partly overlapping and one being interposed between the other two.

The operations above outlined may be repeated in connection with successive orders. It will be understood, of course, that a different series of operations may be employed whenever it is found convenient to vary the system to adapt it to different styles of commercial work. Further it will be apparent that while my invention is shown as applied to a Monarch machine it may be adapted in whole or in part to other styles of typewriting machines and that various constructional changes may be effected without departing from the spirit and scope of said invention.

Some of the features of invention herein described are not herein claimed in their broadest aspects for the reason that they form in part the subject-matter of prior applications filed by me, as follows: Serial No. 526,560, filed November 6, 1909; Serial No. 627,916, filed May 18, 1911; Serial No. 628,165, filed May 19, 1911; and Serial No. 640,295, filed July 24, 1911.

What I claim as new and desire to secure by Letters Patent, is:

1. In a typewriting machine, the combination of a platen having work sheets arranged at opposite ends and partially overlapping at about the middle of the platen, and means for advancing each of the work sheets independently of the other and also for advancing the work sheets together, said means including a paper feeding device arranged opposite one of the end portions of the platen to assist in advancing one of the work sheets, and a second paper advancing device arranged near the opposite end portion of the platen to assist in advancing the other work sheet independently of the first named work sheet, both said devices being outside of the overlapping portions of said work sheets.

2. In a typewriting machine, the combination of a platen having work sheets arranged at opposite ends and partially overlapping at about the middle of the platen,

a transfer strip being interposed between the overlapping portions and means for advancing the two work sheets independently of each other and for advancing the work sheets and transfer strip together, said means including a paper feeding device arranged opposite one of the end portions of the platen to assist in advancing one of the work sheets, a second paper advancing device arranged near the opposite end portion of the platen to assist in advancing the other work sheet independently of the first named work sheet, both said devices being outside of the overlapping portions of said work sheets, and a third paper advancing device for the transfer strip, said third device being opposite the overlapping portions of the work sheets.

3. In a typewriting machine, the combination of a platen having work sheets arranged at opposite ends and partially overlapping at about the middle of the platen, a transfer strip being interposed between the overlapping portions, and means for advancing the work sheets and transfer strip simultaneously through line space distances and for advancing either work sheet separately through either a single line space distance or continuously through a plurality of line space distances.

4. In a typewriting machine, the combination of two platen elements arranged end to end, means for guiding two work sheets over said platen elements in overlapping arrangement, and means operative automatically to couple said two platen elements together.

5. In a typewriting machine, the combination of two platen sections arranged end to end, means for guiding two work sheets over said platen sections in overlapping arrangement and means operating automatically at a predetermined point in the travel of the carriage to couple said platen sections together.

6. In a typewriting machine, the combination of two platen elements arranged end to end, means operative automatically to couple said two platen elements together, a paper feeding device, and means operative automatically to move said device into operative position.

7. In a typewriting machine, the combination of two platen elements arranged end to end, means operative automatically to couple said two platen elements together, a paper controlling device coöperative with the work sheets fed over both platen elements, and means operating automatically at a predetermined point in the travel of the carriage to move said device into operative position.

8. In a typewriting machine, the combination of a platen, means for guiding two work sheets over said platen in overlapping order,

means for guiding a transfer sheet between the overlapped portions of said work sheets, and a paper feeding device for the transfer sheet arranged in the same transverse plane with the overlapped portions of said work sheets and with said transfer sheet.

9. In a typewriting machine, the combination of a platen, means for guiding two work sheets over said platen in overlapping order, means for guiding a transfer sheet between the overlapped portions of said work sheets, a paper feeding device for the transfer sheet arranged in the same transverse plane with the overlapped portions of said work sheets and with said transfer sheet, and means operating automatically to move said device into and out of operative position.

10. In a typewriting machine, the combination of a platen, means for guiding two work sheets over said platen in overlapping order, means for guiding a transfer sheet between the overlapped portions of said work sheet, a paper feeding device for the transfer sheet arranged in the same transverse plane with the overlapped portions of said work sheets and with said transfer sheet, and means operating automatically at a predetermined point in the endwise travel of the platen to move said device into operative engagement with the three sheets.

11. In a typewriting machine, the combination of two platens arranged end to end, means for guiding separate work sheets over said platens in overlapping order, means for guiding a transfer sheet between the overlapped portions of said work sheets, a paper feeding device for the transfer sheet arranged in the same transverse plane with the three sheets, means operating automatically to connect said platens, and means operating automatically to move said device into operative position.

12. In a typewriting machine, the combination of two platens arranged end to end, means for guiding separate work sheets over said platens in overlapping order, means for guiding a transfer sheet between the overlapped portions of said work sheets, a feed roller for the transfer sheet arranged in the same transverse plane with the overlapped portions of the work sheets and with the transfer sheet, means for automatically coupling the platens together, and means for automatically moving the feed roller into and out of operative position.

13. In a typewriting machine, the combination of a platen, means for guiding three work sheets thereover in interleaved relationships, and means for differentially feeding said sheets, said means including separately controllable feed rollers for the different work sheets and a single finger piece which when operated may cause all three sheets to advance together or may cause either of two sheets to be advanced inde-

pendently of the other sheets according as the respective feed rollers for said three sheets are in operation.

14. In a typewriting machine, the combination of a platen, means for guiding three work sheets thereover in interleaved relationship, and means for differentially feeding said sheets, said means including separately controllable feed rollers for the different work sheets and a finger piece which when operated advances the sheets a line space distance and also including a device operative at will to advance either one sheet separately or two sheets together continuously through a plurality of line space distances according as the respective feed rollers for said three sheets are in operation.

15. In a typewriting machine, the combination of a platen, a pair of work sheets arranged at opposite ends of the platen and partially overlapping at about the middle of the platen, and controlling means for advancing said sheets independently of each other or together at will, said controlling means including a paper feeding device arranged opposite one of the end portions of the platen to assist in advancing one of the work sheets, and a second paper advancing device arranged near the opposite end portion of the platen to assist in advancing the other work sheet independently of the first named work sheet, both said devices being outside of the overlapping portions of said work sheets.

16. In a typewriting machine, the combination of a platen, and sets of paper feeding devices coöperative with opposite end portions of the platen and separated by a gap, said gap providing a passage-way for a work sheet around the platen, and a feeding device separated from the platen for said sheet.

17. In a typewriting machine, the combination of a platen carriage, a platen thereon, a roll supporting frame on the carriage, roll holders on said frame carrying continuous sheets, two of said sheets partially overlapping and the third sheet being interleaved between the overlapping portions of the other two, means coöperative with the platen to feed the two overlapped sheets, and a feeding device for the third sheet separate from the platen.

18. In a typewriting machine, the combination of a platen carriage, a platen thereon, a roll supporting frame on the carriage, roll holders on said frame carrying continuous sheets, two of said sheets partially overlapping and the third sheet being interleaved between the overlapping portions of the other two, means coöperative with the platen to feed the two overlapped sheets, and feeding devices comprising a stationary guide and a coöperative feed roll, which devices coöperate with all three sheets.

19. In a typewriting machine, the combination of a platen carriage, a platen thereon, a roll supporting frame on the carriage, roll holders on said frame carrying continuous sheets, two of said sheets partially overlapping and the third sheet being interleaved between the overlapping portions of the other two, means coöperative with the platen to feed the two overlapped sheets, feeding devices comprising a stationary 70 guide and a coöperative feed roll which devices coöperate with all three sheets, and a cam bar on the machine frame for moving said feed roll into and out of coöperative engagement with said stationary guide. 80

20. In a typewriting machine, the combination of a platen carriage, a platen thereon, a frame on said carriage, roll holders on said frame arranged at opposite ends of the platen, and intermediate roll holder, and means for feeding paper around the platen from said roll holders, said means comprising feed rollers separately controllable to feed the paper from each of the end roll holders independently of the other two holders, and 90 also a roller for feeding paper from the intermediate roll holder in conjunction with the other two.

21. In a typewriting machine, the combination of a carriage, a platen thereon, a frame on said carriage, and a plurality of roll holders on said frame, said frame comprising end plates and a connecting cross bar carrying a roller, a trackway on the frame of the machine on which said roller 100 runs, means for affording adjustment of said cross bar, and means for affording adjustment of said trackway.

22. In a typewriting machine, the combination of two platens arranged end to end, one of said platens being provided with a head having an elongated outwardly extending hub and the other platen being provided with a head having an internal sleeve bearing on said hub. 105

23. In a typewriting machine, the combination of two platens arranged end to end, an axle common to said platens, one of said platens having an elongated hub portion extending outwardly and bearing on said axle 115 and fixedly secured thereto, and the other of said platens having an inwardly extending sleeve which surrounds and bears on said hub portion.

24. In a typewriting machine, the combination of a platen carrier, an axle bearing on said platen carrier, two platens arranged end to end and to which said axle is common, one of said platens having a hub and the other of said platens having a sleeve 125 bearing on said hub, and a second elongated sleeve surrounding said axle and abutting against the first sleeve at one end, said second sleeve being rigid with said platen carrier. 130

25. In a typewriting machine, the combination of a platen carrier, a platen, a toothed wheel rigid therewith, a swinging arm, a pawl on said arm co-operative with said toothed wheel, and a stop on said platen carrier normally maintaining said pawl disengaged from said wheel, said stop also co-operating with said swinging arm to determine its normal position.
- 10 26. In a typewriting machine, the combination of a platen carrier, a toothed wheel rigid therewith, an arm co-axial with said platen, a spring tending to turn said arm in one direction, a stop on the platen carrier 15 with which said arm normally co-operates, and a pawl pivoted on said arm and normally co-operating with said stop, said pawl being normally maintained separated from

said wheel by said stop but being adapted to engage the teeth of said wheel when said arm is actuated.

27. In a typewriting machine, the combination of two platens arranged end to end, parallel toothed wheels each connected to one of said platens, means for automatically coupling said wheels, a swinging arm provided with a finger piece, and a pawl pivoted on said arm and co-operative at will with one of said toothed wheels.

Signed at Marcellus, in the county of 20 Onondaga, and State of New York, this 28th day of December A. D. 1911.

HERBERT H. STEELE.
